SPUDDER ATTACHMENT

Harland W. Cardwell, Gerald G. Brown, and Edward V. Hobbs, Wichita, Kans., assignors to Cardwell Manufacturing Company, Inc., Wichita, Kans.

Application September 14, 1948, Serial No. 49,264

2 Claims. (Cl. 74—600)

1

This invention relates to a spudding attachment for drilling rigs and particularly to an attachment for a standard type of drill rig whereby to adapt the rig to operate cable tools.

According to the present invention, an attachment is provided for a standard drilling rig and includes an elongated crank pin mounted for orbital movement about an axis generally parallel to the axis of a cable drum which constitutes part of the basic rig. The elongated crank pin mentioned carries a sheave rotatable thereon and longitudinally slidable therealong. A cable partially wound on said drum is trained over said sheave and thence extends upwardly over a crown pulley carried near the top of a mast or the like thence downwardly to an impact drilling tool. Upon rotation of the crank the cable will be moved in such a manner as to alternately lift and drop the tool to effect piercing of an earth formation. As the cable unwinds from the drum, during downward progress of the hole, the sheave moves longitudinally of the crank pin to align itself with the cable extending from the drum. The spudder attachment of the present invention also includes novel means for adjustably mounting the crank pin on its supporting structure whereby the throw of the crank may be varied.

It is an object of this invention to provide an attachment for a conventional drilling rig to readily adapt the said rig to operate cable tools.

It is a further object of this invention to provide a spudder attachment for a drill rig that is readily and easily mounted on the rig or removed therefrom.

It is a still further object of this invention to provide a spudder mechanism employing a crank to be continually rotated in one direction and upon which crank a cable-engaging sheave is mounted for rotation and longitudinal sliding movement.

It is another object of this invention to provide a spudder attachment employing a rotatable crank and in which the throw of the crank may be varied.

It is a still further object of this invention to provide a spudder mechanism of rugged yet simple construction which is economical to manufacture, involving no complicated machining process.

Other and further objects and advantages will appear to those skilled in the art as the detailed description proceeds in connection with the accompanying drawings, wherein:

Figure 1 is a side elevational view of a more or less conventional drill rig with the spudder

2

attachment of the present invention mounted thereon.

Figure 2 is a perspective view of the spudder attachment of the present invention.

Figure 3 is an end view of the crank element of the spudder of this invention, and

Figure 4 is a sectional view, with certain parts shown in elevation, taken substantially along the line 4—4 of Figure 3 and looking in the direction of the arrows.

Referring to Figure 1, the numeral 1 indicates generally a more or less conventional form of drilling rig and comprises a base portion 2 with a superstructure 3 thereon. The superstructure

3 supports a motor 4 and cable winding drums 5 and 6. It is to be understood that the usual transmission and control mechanisms whereby the motor 4 may selectively drive the drums 5 or 6 are contemplated but omitted from Figure 1 of the drawings for clarity of illustration. Such control and transmission mechanisms form no part of the present invention and need not be described in detail, suffice it to say that such means are contemplated.

An upstanding framework 7 is carried at the rearmost end of the frame 2 and an upstanding framework 8 is carried at the forward end thereof. The framework 8 includes a transversely extending shaft or bar 9 at the upper end thereof to which a mast 10 is pivoted. As shown in Figure 1, the mast is in its erected position but it will be clear that the mast may be rotated counter-clockwise about the shaft 9 to lie generally horizontally with the rearwardly extending portion thereof resting upon the frame 7. The mast 10 includes a downwardly extending foot 11 engaging a stop block 12 and bearing upon a transverse frame member (not shown) whereby the mast may be properly located in its erected position. The mast 10 further carries a rotatable sheave 13 adjacent the upper end thereof.

The spudder attachment of the present invention is indicated generally by the numeral 14 and includes means providing an axis 15 fixedly mounted on the rig frame, crank arms 16, a crank pin, sheave 17, and means whereby the sheave is caused to move in an orbital path about the axis 15.

A cable 18, wound upon the drum 5 extends over the sheave 17 then upwardly and over the sheave 13 and downwardly to an impact drilling tool 19 of usual construction. The cranks 16 are caused to rotate by a sprocket wheel 20 driven by a chain 21 from a sprocket wheel 22 on the shaft of the upper drum 6.

It will be clear that as the shaft of the upper drum 6 is caused to rotate continuously in one direction, the chain 21 and sprocket wheel 20 will cause the sheave 17 to move about the axis 15 and will be effective to lift the tool 19 during part of its rotation and to allow the tool to drop during the remainder of a cycle of rotation of the sheaves 17. As successive impacts of the tool 19 cause a hole being pierced in the earth formation to increase in depth, the drum 5, upon which cable 18 is wound, may be intermittently or continuously rotated at the proper rate to cause the tool 19 to follow the deepening bore hole.

The axis 15 is provided by stub shafts 23 and 24 (see Figure 2) mounted in bearings 25 on an auxiliary framework 26. The framework 26 is so constructed and shaped that it readily engages certain portions of the drilling rig superstructure 3 to which it may readily be bolted or otherwise fastened as indicated in Figure 1 of the drawings.

The bearing brackets 25 are bolted or otherwise fastened to the framework 26 and include upwardly extending portions 27 which are threaded at their ends and passed through a slot in a bracket 28 carried by the frame 26. Nuts 29 and 30 are threadedly engaged with the threaded ends of the extensions 27 and are located on opposite sides of the brackets 28. Loosening of the bolts holding the bearing members 25 to the frame 26, will enable the nuts 29 and 30 to be manipulated in an obvious manner to effect proper axial alignment of the bearings 25 and to effect proper tensioning of the chain 21.

The stub shafts 23 and 24 are mounted in axial alignment and the sprocket wheel 20 is mounted on the outer end of the stub shaft 23 and held thereon by means of a key or in any other suitable manner. The sprocket wheel 20 is shown removed from the stub shaft 23 in Figure 2 of the drawings, which is merely for clarity of illustration. It is to be understood that in the assembled attachment the sprocket wheel 20 is rigidly mounted on the outer end portion of the stub shaft 23.

Figure 2 also shows the sprocket wheel 22 referred to above, and a clutch indicated generally at 31 to effect engagement or disengagement of the said sprocket wheel 22 from the shaft of the upper drum 6 upon which it is mounted. The clutch 31 may be operated by means of a lever 32, located adjacent the operator's position, through suitable links and levers 33 and 34.

As stated previously, the stub shafts 23 and 24 are in axial alignment and carry at their inner ends radially extending crank arms to be described. Figure 3 illustrates one of the crank arms and as shown therein, a filler block 35 and reinforcing plates 36 are welded or otherwise rigidly secured to the end of the shaft 23. A split ring 37 is welded or otherwise rigidly secured to the filler block 35 and the plates 36 and is provided with outwardly extending lugs 38 through which bolts 39 extend and which may be tightened to compress the split ring 37 for a purpose to be later described. The stub shaft 24 includes identical elements to those just described and it will be seen that the blocks 35, plates 36, and rings 37 constitute crank arms on the shafts 23 and 24. The split rings 37 define cylindrical bores or openings 40 in which cylindrical members 41 are positioned. The cylindrical members 41 may be provided with recesses 42 (see Fig. 4) of such size and configuration as to snugly receive an elongated, preferably tubular, crank pin 43. The recess 42 in the cylindrical member 41 is located

eccentrically of the said cylindrical member and it will be readily seen that rotation of the said cylindrical members in the bores 40 will be effective to position the crank pin 43 at different distances from the axis of the shafts 23 and 24. The axis of the shafts 23 and 24 is the axis 15 referred to in connection with Figure 1.

The crank pin 43 may, of course, be solid if desired, but will preferably be rigidly united to the cylindrical member 41 such as by welding or the like. The recess 42 constitutes merely one means for attaching the crank pin 43 to the block 41 and it will be obvious that other expedients may be employed for this purpose.

Upon rotation of the cylindrical members 41 in the bores 40 to position the axis of the crank pin 43 at the desired radius, the bolts 39 may be tightened thus clamping the split rings 37 to the cylindrical members 41 thus fixing the crank pin 43 in its adjusted position. To further insure proper positioning of the member 41 in the bore 40 and to insure its being held in that position, the members 41 are provided with shear blocks or abutments 44, welded or otherwise rigidly attached to the outer face thereof. A bar 45 is positioned between the said shear blocks 44, in the manner illustrated in Figure 3 and is removably attached to the said member 41 by means of bolts or cap screws 46. The outer end portion of the split ring 37 is likewise provided with diametrically opposed pairs of shear blocks 47, the blocks of each pair being spaced apart a distance equal to or slightly greater than the width of the bar 45. The shear blocks or abutments 47 may be formed integrally with the split ring 37 or may be welded thereto or fashioned in any other desirable manner. It is to be understood that the pairs of abutments 47 on one split ring correspond in angular position to the pairs on the other split ring. The crank pin 43 may be provided with an opening 48 adjacent one end thereof.

To effect adjustment of the crank pin 43 the bolts 46 and bars 45 may be removed from the ends of the members 41, the bolts 39 may be loosened to release the split rings 37 and upon insertion of a bar or other suitable lever means in the hole 48, the crank pin 43 and block and members 41 may be rotated in amounts sufficient to effect the desired adjustment. Such positions of adjustment will preferably correspond to the angular positions of the pairs of lugs 47. After the desired adjustment is made, bolts 39 may be again tightened and the bars 45 replaced to extend between the lugs 44 and 47 and upon replacing the bolts or cap screws 46 the crank pin will obviously be locked in its adjusted position.

As previously described the sheave 17 is provided with a central opening of such dimension that it will freely rotate upon the crank pin 43 under the influence of the cable 18 and is freely slidable longitudinally of the said crank pin. Such a structure is commonly known as a "fleeting" sheave.

The auxiliary frame 26 previously referred to preferably includes cross members 49 and 50 and may include diagonal brace members 51. The various elements of the auxiliary frame 26 may be bolted or welded together or may be assembled in any other suitable manner.

Preferably the auxiliary frame 26 is provided with clevis members 52 which may be engaged with the main frame 2 in the manner shown in Figure 1 to properly tension the members to eliminate vibrations and to unite the attachment to the drilling rig in a rigid manner.

Although not shown, it is contemplated that the chain 21 and sprocket wheels 20 and 22 be provided with a suitable protective cover or housing. It is also contemplated that the fleet-ing sheave 17 be provided with a suitable cover or housing movable therewith longitudinally of the crank pin and independently rotatable thereon to enable it to be maintained in a pre-determined position of vertical orientation. Such orientation could be maintained by attach-ing a weight to one side of the housing.

Although a single specific embodiment of the invention has been shown and described, it is clear that other modifications may be resorted to within the scope of the invention as defined in the appended claims.

We claim:

1. In a spudding attachment for well drilling apparatus, a frame, a pair of axially spaced and aligned stub shafts journaled on said frame, crank arms on adjacent ends of said stub shafts, an elongated crank pin extending between the ends of said crank arms, means for rotating said stub shafts continuously in one direction, each of said crank arms having a cylindrical bore therethrough parallel to the axis of said stub shafts, a cylinder rotatably mounted in each of said bores, each of said cylinders being of a length substantially equal to the length of said bores, the ends of said crank pin being eccentrically attached to said cylinders whereby to change the throw of said crank pin upon rota-

tion of said cylinders in said bores, diametrically extending bars removably attached to the outermost end faces of said cylinders and projecting radially therebeyond in overlapping relation to portions of said crank arms, the said portions of said crank arms being provided with fixed abutments adjacent opposite sides of said bars whereby to lock said cylinders against rotation in said bores.

10 2. A spudding attachment as defined in claim 1 wherein said bores are defined by split sleeves and wherein means are provided to clamp said split sleeves to the peripheries of said cylinders.
